MERVIL N. PLAYFAIR, OF ALMONTE, ONTARIO, CANADA.

VALVE-CLOSER.

1,280,293.

Specification of Letters Patent.

Patented Oct. 1, 1913.

Application filed December 27, 1917. Serial No. 208,189.

To all whom it may concern:

Be it known that I, MERVIL N. PLAYFAIR, a subject of the King of Great Britain, residing at Almonte, in the Province of Ontario and Dominion of Canada, have invented certain new and useful Improvements in Valve-Closers, of which the following is a specification.

This invention relates to an improved device for turning a valve such as used in connection with a steam or hot water boiler, principal reference being had to the valve used at the water glass. It often happens that a water glass will break and it is impossible to turn the valve without burning the hand. With this invention, the valve can be turned and shut off without it being necessary to approach close to the valve thus doing away with the danger of burning or scalding by hot water or steam. This attachment will be mounted upon the valve stem in place of the usual hand wheel and is so constructed that the housing holding the sprocket chain in place upon the pinion or sprocket wheel will be held in the proper position of its own weight.

This device will be further so constructed that it does not require any special construction of valve thus permitting it to be used in connection with valves already installed.

This invention is illustrated in the accompanying drawings, wherein:—

Figure 1 is a view showing the housing in front elevation,

Fig. 2 is a side elevation of the housing shown in Fig. 1,

Fig. 3 shows a front elevation and a side elevation of the forward wall of the housing,

Fig. 4 shows a front elevation and a side elevation of the sprocket wheel mounted in the housing,

Fig. 5 is a vertical sectional view showing the attachment in place upon a valve stem shown in elevation, and

Fig. 6 is a front elevation showing the attachment in place.

This attachment is to be mounted upon a valve stem 10 and includes a housing 11 having side walls 12 extending about its upper portion and provided with sockets 13 to receive fastener screws 14 holding a forward wall 15 in place. This forward wall 15 has a central portion cut out as shown at 16 thus providing an opening, the purpose of which will be hereinafter brought out. This housing has the lower portion of its inner or

rear wall thickened to provide a weight 17 serving to retain the housing in the position shown in Fig. 5 upon the valve stem 10, the upper portion of the weight or thickened section of the rear wall being provided with a passage 18 through which the valve stem 10 will pass. A pinion or sprocket wheel 19 is provided with a squared center opening 20 to receive the reduced and squared end portion 21 of the valve stem 10 thus rigidly mounting this sprocket wheel upon the valve stem in place of the usual turning head when the sprocket wheel is put in place and the securing nut 22 tightened. A turning key 23 extends through the cutout or opening 16 and is connected with the sprocket wheel by screws or other fasteners 24 which pass through the seat 25 of the key. It will thus be seen that under ordinary circumstances, the valve may be opened and closed through the medium of this key 23 in the manner that a valve would be opened or closed through the medium of the usual turning head. In order to permit the valve to be turned from a point at a distance from the water glass in case the glass should break, there has been provided a sprocket chain 26 which passes about the sprocket wheel 19 and may be led to any point desired. By grasping the sprocket chain and drawing it longitudinally, the sprocket wheel and valve stem can be rotated, thus closing the valve and shutting off the steam or water when the glass bursts. This sprocket chain may be connected at its ends to provide an endless chain so that the valve can be completely shut off.

It will thus be seen that there has been provided an attachment for a valve so constructed that the valve may be safely shut off when the glass breaks and further that there has been provided an attachment which can be put in place upon a valve of a conventional construction and further that there has been provided an attachment including a housing which will serve as a guide to retain the sprocket chain upon the sprocket wheel which housing will be so constructed and mounted that it will be retained in the position shown in Fig. 5 by its own weight.

What is claimed is:—

1. The combination of a valve stem, a housing loosely mounted upon the valve stem and having its lower end portion weighted to retain the housing in a set position upon the stem, a sprocket wheel rigid upon the

valve stem within the housing, the forward wall of the housing having its center portion cut away to provide a passage, a turning key extending through the passage and secured to the sprocket wheel, and a sprocket chain extending through the housing and having its links in engagement with the links of the sprocket wheel.

2. The combination of a valve stem, a housing loose upon the valve stem and having its lower portion thickened to provide a weight retaining the housing in a set position, the upper portion of the housing being provided with side walls, a forward wall connected with the side walls and positioned in spaced relation to the lower portion of the housing, a sprocket wheel rigid upon the valve stem within the housing, and a sprocket chain passing about the sprocket wheel and extending from the housing beneath the end portions of the side walls.

3. A valve stem, a housing loose upon the

valve stem and having a forward wall provided with a cutout, a sprocket wheel rigid upon the valve stem within the housing, a turning key extending through the cutout of the forward wall and connected with the sprocket wheel and a sprocket chain extending about the sprocket wheel within the housing and extending from the housing.

4. The combination of a rotatable valve stem, a turning wheel fixed to rotate with said stem, an actuating chain engaged with said wheel, and a housing loosely mounted on said stem and inclosing said wheel to retain the chain in engagement therewith, said housing having the forward wall thereof removable to give access to the interior thereof.

In testimony whereof I affix my signature in presence of two witnesses.

MERVIL N. PLAYFAIR.
